CEILING CONSTRUCTION AND SLAB
THEREFOR

Clarke F. Davis, Short Hills, John G. Brush, Westfield, and Lyle K. Mayne, Linden, N. J., assignors to American Cyanamid & Chemical Corporation, New York, N. Y., a corporation of Delaware

Application July 19, 1935, Serial No. 32,166

13 Claims. (Cl. 72—68)

The present invention relates to a building construction including a ceiling made or composed of precast units and to the units going to make up such construction.

5 The principal object of the invention is the provision of a ceiling construction of the above type which may be erected without difficulty, which will have desirable rigidity and which does not require any special beam or ceiling support 10 spacing to carry the same.

Another important object of the invention is the provision of slabs of the precast type which may be cheaply manufactured, which may be erected to form a ceiling with minimum fitting 15 but which, when so erected, will insure a flat ceiling, such units being so constructed that they may be picked up and suspended from an overhead support at any point without regard to such support spacing.

To this end, the invention contemplates in a 20 ceiling construction a series of precast slab units the opposite edges of which are provided with complementarily engaging parts so as to permit the centering of one slab edge against its previously erected neighbor. These complementarily engaging parts on adjacent slab edges may or may not constitute a support for the edge of the slab being erected, although in all cases interengaging edges will assist materially in such 25 support. It is contemplated that each slab will be hung primarily from near one longitudinal edge and that edge the one away from the row of slabs previously erected. In order to temporarily support the opposite longitudinal edge 30 of the slab being erected, means are provided on such slab for engagement with its previously erected neighbor to support the same while the supporting means at the opposite edge of the slab is being engaged. Where such temporary 35 supports remain in place, as they usually do, they assist materially in contributing to the support of the entire slab.

Means are provided on the slabs to engage the 40 hanger means in any desired location without regard to the overhead supports from which the hangers are suspended. As a result thereof, no special support spacing is required.

After a slab has been erected in place, removable dowels in the slab may then be driven partially therefrom into its previously erected neighbor, which contributes materially to the rigidity of the entire structure to maintain a flat ceiling where the development of cracks 45 after being finished is reduced to a minimum.

The invention further consists in the specific slabs going to make up such a ceiling.

The invention also consists in the novel arrangement, construction and combination of parts more fully hereinafter described and shown 5 in the accompanying drawings, in which—

Fig. 1 is a plan view of a ceiling slab constructed according to this invention;

Fig. 2 is a partial perspective of a section of ceiling showing the manner of erecting the individual slabs;

Fig. 3 is a sectional view along the line 3—3 of Fig. 1;

Fig. 3a is a perspective view of an embedded stirrup;

Fig. 4 is a sectional view along the line 4—4 of Fig. 1;

Fig. 5 is a partial perspective view of a slab showing a modified hanging means;

Fig. 6 is a perspective view of a modified form 20 of slab;

Fig. 7 is a sectional elevation along the line 7—7 of Fig. 6;

Fig. 8 is a sectional view along the line 8—8 of Fig. 7;

Fig. 9 is a top plan view of a modified form 25 of slab;

Fig. 10 is a sectional view along the line 10—10 of Fig. 9;

Fig. 11 is a top plan view of a modified form 30 of slab;

Fig. 12 is a perspective view of a section of a ceiling showing the manner of using the slab of Fig. 11;

Fig. 13 is a transverse sectional view of the 35 slab of Fig. 11;

Fig. 14 is a sectional view along the line 14—14 of Fig. 13;

Fig. 15 is a perspective view of the hanger engaging means of the slab of Fig. 11.

Referring now with particularity to that type of slab shown in Fig. 1, the slab body is shown at 1 of any desired material which may be cast and which will take a set. Such a cementitious material as gypsum is admirably adapted for this use either with or without fillers. Suitably embedded in the slab body at the time of casting are two longitudinal reinforcements 2. These may be of any desired type, although elements of a channel nature are desired because of cheapness, strength and other considerations which will appear as the description proceeds.

Hanger engaging means are provided in the form of an inverted stirrup element, one of which is shown in Fig. 3 at 3 with its main body em- 55

bedded just below the upper surface of the slab 1 and its lower ends 4 embedded well down into the slab body to prevent withdrawal. If the main portion 3 of the stirrup or hanger engaging means is only embedded slightly below the surface of the slab it does not serve as a lateral reinforcement and, as a matter of fact, this is not needed, inasmuch as other reinforcements will be provided as will appear hereafter.

10 Intermediate the ends of the member 3, two loops are provided as at 5 and 6 respectively in planes at right angles to each other and projecting slightly above the surface of the slab.

15 Other shorter stirrups 7 are provided in the same slab having a similar configuration to that just described, although of less extent. These shorter stirrups 7 are likewise provided with loops 5 as in the case of the longer elements 3.

20 It is desirable that the opposite longitudinal and lateral edges of each slab be provided with complementary configurations. This may take the form of tongues and grooves 9 or the shiplaps shown in the slab of Fig. 6 or any combination thereof. The tongues 8 and grooves 9 are preferred on the longitudinal edges for reasons which will presently appear.

25 When erecting slabs of this character to form a ceiling, the first row may be suspended by hangers such as that shown at 10 in Fig. 3 engaging the loops 6 at one end and a furring channel 11 which is, in turn, suspended from a beam 12 by intermediate member 13 or the hanger 10 may engage the beam 12 direct as shown in Fig. 4. At the other edge of the slab an elongated rod 14 having an offset portion 15 is threaded through at least two of the loops 5 in the manner shown in Fig. 2 and the end of the hanger 10 engaged therewith. The hanger 10 may, of course, either be supported from the furring or beam as the case may be. Due to the fact that the rod 14 may be of any desired length or placed between two or more loops 5, a considerable flexibility of location is permitted, and the hanger 10 may hook onto the overhead support at the nearest location without regard to any special spacing of such supports. This is a very desirable feature.

30 Each slab is provided, at the time of casting, with a removable dowel 16 (Fig. 3), the end of which is indicated at 17 in Fig. 2. When the first slab has been erected, a nail set or the like is placed against the end 17 of the dowel 16 and by means of a hammer, the dowel is partially driven from the slab in which it occurs into the wall against which the first slab is erected.

35 After the first row of slabs has been thus erected, a second row is begun. This is well represented by the slab B of Fig. 2, where the slab A represents one of the first row. One longitudinal edge of the slab B is placed adjacent the edge 60 of the slab A and by reason of the complementary tongue and groove there, the slab B is definitely centered on the previously erected slab. An elongated rod 18 is then passed through the slab B, one end of said rod extending over the top of slab A. If preferred, the rod 18 may be inserted through the loop 6 prior to placing slab B in position, whichever may be found most expedient. Inasmuch as each slab is provided with at least two of the loops 6 as shown in Fig. 1, such slab is temporarily supported in the proper location by means of these rods 18 assisted by the complementary tongue and groove without effort by the workman. A hanger engaging element 15 as above described is then passed through loops 5 at the opposite edge of the slab B and the hanger

10 made to engage this rod and the overhead support in the manner described in connection with slab A. Any suitable number of rods 14 may be used, dependent upon the length of the slab. After such slab has been erected, its dowel or 5 dowels may then be partially driven therefrom into the slab A, all of which serves to more or less permanently secure the slabs together to form a particularly rigid ceiling having a perfectly flat undersurface. As a result of this construction, 10 when such a surface is plastered, as is usual, there is a minimum tendency to develop cracks due to the fact that each slab is tied to its neighbor and the whole contributes to the rigidity of such a construction. 15

Fig. 5 illustrates a modified form of hanger in the form of a strip 19, the use of which makes unnecessary the offset 15 in the rod 14.

20 A modified form of slab is shown in Fig. 6 embodying, however, the same principles of construction as have been previously described. This slab is provided with the short stirrup-like elements 7 having an exposed portion 20 bridging a longitudinal channel which runs the entire length of the slab and near one edge thereof. In 25 such case, the rod 14 may be made to pass beneath any two or more exposed portions of the stirrups 7 and the hanger 10 engaged therewith as before. In such a slab, the same system of temporary support by a short rod 18 in engagement with the loop 6 is likewise provided.

25 In this case, the slab may be provided with complementary shoulders 22 and 23 forming shiplaps which materially assist in locating the edge of the slab being presently erected, while at the same time assisting in the support of that edge.

30 The loop 6 may be formed as a part of a long stirrup 3 as in Fig. 3 or by means of a spring clip as shown in Figs. 13 and 14, which will be more fully described hereinafter.

35 In Fig. 9, long stirrups 3 and two channels 21 are used. This enables two series of hangers 10 to be used in place of the single series in Fig. 7.

40 In this case, it is desirable to form the loops 6 by means of a spring clip having spaced apart legs 24 sprung into holes in a longitudinal reinforcement 2. This is shown in more detail in Fig. 14. This makes possible the use of the short rod 18 in erection.

45 Another desirable form of slab is shown in Figs. 11 to 15 inclusive wherein in place of the stirrups and the rod 14, a hanger engaging element 25 of sheet or strip metal is used. In this form of construction, the hanger 25 is provided with downwardly extending ears 26 perforated 50 as at 27 to receive the dowels 16, which serves to tie the hanger into the slab in the proper location. Intermediate the ears 26 the hanger engaging element is of a narrower width and provided with a series of perforations 28 to receive the hanger 10 wherever it may occur. The upper portion of the hanger engaging element 25 preferably though not necessarily projects within the channel 21. 55

60 This present type of slab is erected in the same manner as those previously described, making use of the rods 18 passing through the loops 6, etc. As to the use of dowels in such slabs, obviously any number may be used depending upon the length of such slabs and these dowels serve 65 not only to tie the slabs together but also as lateral reinforcements during handling and after erection.

65 While the invention has been shown and described with reference to particular embodiment 75

ments, yet these are to be taken as illustrative only and the invention is to be construed broadly and limited only by the scope of the claims.

We claim:

5. 1. A ceiling comprising a plurality of precast slabs, one of said slabs being hung from an overhead support, a second slab adjacent the first slab and having support receiving means partially projecting from the face thereof, and supporting means passing beneath the receiving means and projecting onto the top of the first slab, whereby the second slab is at least partially supported at one edge by the first slab, and means to hang the opposite edge of the second slab from 10 an overhead support.

15. 2. The ceiling of claim 1 in which the support receiving means includes a loop.

3. The ceiling of claim 1 in which the support receiving means includes a loop and the supporting means includes an elongated element passing through the said loop and projecting over the first slab.

4. The ceiling of claim 1 with complementary means on the adjacent edges of the two slabs to 25 center the edge of the second slab on the first slab.

5. The ceiling of claim 1 with a dowel in the second slab partially embedded in the first slab.

6. A precast slab of set cementitious material 30 having a plurality of stirrup elements embedded therein, a portion of each stirrup being exposed and a hanger engaging element threaded beneath the exposed portions of at least two stirrups in which the slab is provided with a longitudinal channel in one face thereof, each stirrup extending across said channel.

35. 7. A precast slab of set cementitious material having a plurality of stirrup elements embedded therein, a portion of each stirrup being exposed

and a hanger engaging element threaded beneath the exposed portions of at least two stirrups in which the slab is provided with a longitudinal channel in one face thereof, each stirrup extending across said channel, the slab being shiplapped. 5

8. A precast slab of set cementitious material having an inverted stirrup element embedded therein, said element having two loops formed therein and projecting above the slab face, the 10 plane of one loop being at right angles to the plane of the other loop.

9. A precast slab of set cementitious material having a longitudinal channel in one face thereof and a hanger engaging element partially embedded in said slab and bridging said channel crosswise thereof. 15

10. A precast slab of set cementitious material having a longitudinal channel in one face thereof and a hanger engaging element partially embedded in said slab and projecting into said channel in which the hanger engaging element is perforated within the channel. 20

11. The slab of claim 9 with a dowel also embedded in the slab and passing through the lower end of said hanger engaging element. 25

12. The slab of claim 9 said hanger engaging element comprising a strip of metal having a row of perforations therein and depending ears 30 penetrated by lateral dowels embedded in said slab.

13. The slab of claim 9 with a longitudinal reinforcement in said slab and a clip secured thereto and having a portion projecting above the face of said slab. 35
